United States Patent Office

Des. 181,803
Patented Dec. 31, 1957

181,803

MEDALION

Hubert E. Milks, Copemish, Mich.

Application December 5, 1956, Serial No. 44,073

Term of patent 14 years

(Cl. D29—19)

Fig. 1

Fig. 2

Fig. 1 is a plan view of the medalion embodying my new design;

Fig. 2 is a side view thereof.

The side of the medalion not shown, is plain.

The dominant features of the design reside in the portion shown in full lines.

I claim:

The ornamental design for a medalion, as shown and described.
